UNITED STATES PATENT OFFICE.

MARTIN D. KUHLKE, OF AKRON, OHIO.

DESIGN FOR A VEHICLE WHEEL-TIRE.

48,066.

Specification for Design.

Patented Nov. 2, 1915.

Application filed July 14, 1915. Serial No. 39,934. Term of patent 14 years.

To all whom it may concern:

Be it known that I, MARTIN D. KUHLKE, a citizen of the United States, and a resident of Akron, in the county of Summit and State of Ohio, have invented a new, original, and ornamental Design for Vehicle Wheel-Tires, of which the following is a specification, reference being had to the accompanying drawing, forming part thereof.

The figure presented is a view in side elevation of a portion of a vehicle wheel tire, showing my new design.

I claim:

The ornamental design for a vehicle wheel tire, substantially as shown.

MARTIN D. KUHLKE.
